UNITED STATES PATENT OFFICE

92,995

DESIGN FOR AN ELECTRIC MASSAGER

Mathew Andis, Racine, Wis.

Application February 5, 1934, Serial No. 50,619

Term of patent 14 years

To whom it may concern:

Be it known that I, MATHEW ANDIS, a citizen of the United States, residing at Racine, in the county of Racine and State of Wisconsin, have invented a new, original, and ornamental Design for an Electric Massager, of which the following is a specification, reference being had to the accompanying drawing, forming part thereof.

In the drawing:

I claim:

The ornamental design for an electric massager, as shown.

MATHEW ANDIS.
